UNITED STATES PATENT OFFICE.

JACOB W. BEYRON, OF JACKSON, OHIO.

REIN-SUPPORT.

SPECIFICATION forming part of Letters Patent No. 447,656, dated March 3, 1891.

Application filed September 29, 1890. Serial No. 366,546. (No model.)

To all whom it may concern:

Be it known that I, JACOB W. BEYRON, a citizen of the United States, residing at Jackson, in the county of Jackson and State of Ohio, have invented certain new and useful Improvements in Rein-Supports; and I do hereby declare that the following is a full, clear, and exact description of the same, reference being had to the annexed drawing,

10 making a part of this specification, and to the letters of reference marked thereon.

This invention relates to certain new and useful improvements in rein holders or supports; and it has for its object to provide a 15 simple and cheap device for this purpose, wherein the reins may be readily inserted or removed, but which will effectually hold them against accidental displacement.

The novelty resides in the peculiarities of 20 construction of the holder, as will be herein-after more fully described, shown in the drawing, and then specifically defined by the appended claim.

The invention is clearly illustrated in the 25 accompanying drawing, which, with the letters of reference marked thereon, forms a part of this specification, and in which the drawing is a side elevation showing one form of my holder applied to a saddle.

30 Like letters of reference indicate like parts in the view.

Referring now to the details of the drawing by letter, A designates a base-piece, which, as shown, has formed integral therewith at 35 each end two hooks or arms *a*, which are so bent or turned as to overlap to form substantially a split ring. The ends of the arms ex-

tend beyond each other to guard the opening between them. The base-piece is formed between its longitudinal center and the arms *a* 40 at one end with a clip or lug *b*, designed to engage against the saddle, or a hook thereon, if preferred, to steady the attachment and prevent side movement of the attachment, as seen. It may also be provided centrally with 45 a piece *c* to serve the same purpose.

In practice the reins are placed in the holder by twisting them so that they will be upon edge vertically and then turned into a flat position, where they will be held in the loops 50 formed by the arms. They cannot accidentally be removed; but when it is desired to remove them all that is necessary to do is to turn them upon edge, when they will readily pass through between the arms.

55 The device may sometimes be employed for other purposes than as rein-holders.

What I claim as new is—

As an improved article of manufacture, a rein-holder comprising in a single piece of 60 material an angularly-bent base-piece with open rings or loops at the ends, the ends of each two arms forming the rings extended past each other, leaving a vertical space between them, and a lug to prevent side movement of 65 the holder when in position, substantially as shown and described.

In testimony that I claim the above I have hereunto subscribed my name in the presence of two witnesses.

JACOB W. BEYRON.
